[57] CLAIM

The ornamental design for a watch, as shown and described.

DESCRIPTION

FIG. 1 is a front elevational view of a watch showing my new design with the cover opened, the broken-line showing of a band being environmental only and forms no part of the claimed design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and

FIG. 7 is a bottom plan view thereof.
